EX

Design No. 12,143, dated January 25, 1881.

UNITED STATES PATENT OFFICE.

JAMES H. THORP, OF BROOKLYN, NEW YORK.

DESIGN FOR GIMP.

SPECIFICATION forming part of Design No. 12,143, dated January 25, 1881.

Application filed December 7, 1880. Term of patent 7 years.

To all whom it may concern:

Be it known that I, JAMES H. THORP, of Brooklyn, in the county of Kings and State of New York, have originated and invented a new and original Design for Gimps, of which the following is a full, clear, and exact description, reference being had to the accompanying photographic illustration, making part of this specification.

10 The said photograph represents a face view of my new gimp.

The body of the gimp has scalloped edges $a a$, and between these edges is a series of oval-shaped figures, $b b$, which are traversed lengthwise by two central bands, c and d , running over and under one another alternately, and each showing alternately on the surface, as at $c c c$ and $d d d$. The band c forms one end of each of the oval figures b , while the band d 15 passes over and covers the other end of each of the oval figures b , and each oval figure contains in its center a portion of the band d near

the end which is formed by the band c , and also a portion of the band c near the end which is covered by the band d , so that two 25 separate parts or pillars of the band c and two separate parts or pillars of the band d are in each of said oval figures.

1 claim—

1. The design for a gimp, consisting of the 30 oval figures $b b b$ and the central interchanging bands, c and d , each of which bands occurs in two separate parts or pillars in each of the oval figures b , substantially as shown.

2. The design for a gimp, consisting of the 35 scalloped edges $a a$, inner oval figures $b b$, and central bands, c and d , each of the bands appearing in two separate parts in each of the oval figures, substantially as shown.

JAMES H. THORP.
